AXEL UNO SÄRNMARK, OF STOCKHOLM, SWEDEN.

SELECTIVE CONTROL SYSTEM.

1,347,715.

Specification of Letters Patent. Patented July 27, 1920.

Application filed September 9, 1916. Serial No. 119,196.

To all whom it may concern:

Be it known that I, AXEL UNO SÄRNMARK, a subject of the King of Sweden, residing at Stockholm, in the Kingdom of Sweden, have invented a new and useful Improvement in Selective Control Systems, of which the following is a specification.

This invention relates to a selective control system for operating apparatus at a receiving station by means of electric pulsations which may be sent from a sending station through one or several conductors with or without the earth as return conductor. The invention is primarily intended for telegraphing type-writing, but it may also be used for operating signal devices, for igniting mines and for other arbitrary purposes when it is required to effect from a distance a desired adjustment or regulation.

The invention is broadly characterized by this that at the sending station means are provided for sending to the receiving station positive as well as negative pulsations in variable sequence and number, while at the receiving station there is provided at least one relay or the like adapted to be actuated by the positive pulsations (so-called plus-polarized relay), and at least one relay or the like adapted to be actuated by the negative pulsations (minus-polarized relay), which relays effect the closing and breaking of different local circuits at the receiving station, according to the sequence and the number of the positive and negative pulsations received. In these local circuits the receiving devices, such as for instance lamps, electromagnets, or the like, to be operated, are connected. If thus for instance one positive pulsation and immediately thereafter a negative pulsation are sent from the sending station a certain lamp at the receiving station will become lighted; again, if two positive and one negative pulsation are sent out, another lamp at the receiving station will become lighted, and so forth.

The present arrangement possesses several very important advantages. In the first place its function is independent of the resistance in the conductor between the two stations and thus to a certain extent of the strength of the current in the conductor, provided of course that the current is sufficient for operating the relay. Moreover, by using positive as well as negative pulsations the advantage is attained that the line

always becomes discharged again, hence the pulsations may follow closely to each other, so that the transmitting of the signals may take place exceedingly rapidly and surely even with long lines with comparatively great capacity.

In the accompanying drawings a few embodiments of the present invention have been shown diagrammatically by way of example. Figure 1 the immediate purpose of which is to illustrate the very fundamental principle of the invention, shows an arrangement for signaling at a distance with the use of a single conductor and the earth as return conductor. Figs. 2 to 5 show some minor modifications of the receiving station of this arrangement. Fig. 2 shows a parallel connection of the plus-polarized and minus-polarized relays, Fig. 3 shows a connection for using only one plus-polarized relay at this station, Fig. 4 shows a modification of the connection according to Fig. 3, and Fig. 5 shows a further connection for using only one plus-polarized relay at the receiving station without any additional local battery. Fig. 6 illustrates how the invention may suitably be applied for telegraphing type-writing with the use of a double conductor (for instance two telephone wires) and the earth, in the place of which latter a third wire may, of course, also be used if desired.

Referring to Fig. 1, A denotes a sending station and B a receiving station which stations are connected with one another by means of a single-wire conductor 1 with the earth as return conductor (or by means of a double-wire conductor if desired). At the sending station the embodiment illustrated is provided with three elements for giving signals, shown as keys I, II, and III, to which correspond three receiving elements I', II', and III' at the station B. These receiving elements are here supposed to consist of small incandescent lamps, electromagnets or the like. At the sending station there is further provided a battery 2 the middle point of which is grounded, and a rotary contact drum 3 (which is supposed to be cut open on the line C—D and is shown developed). The contact drum is made of insulating material and in the surface of the same a number of conductive members are embedded. Two of these members consist of rings 4 and 5 around the drum, the former of which is provided with a short laterally projecting bar 6, the other

members consisting of a number of bars, 7 to 13, parallel to one another and to the axis of rotation of the drum. Every second of these bars, viz. 7, 9, 11, and 13 which are of decreasing lengths are connected with one another and with the ring 4 while the other bars 8, 10, and 12 which are of the same length, are connected with each other and with the ring 5. A plurality of contact brushes 14 to 21 bear against the surface of the drum, the two latter of these brushes not being included, however, in the connection illustrated. The brush 15 is connected to the positive pole of the battery 2, while the brush 17 is connected to a point of the battery between its middle point and its negative pole, on account of which the ring 5 and the bars 8, 10, and 12 connected to the same will always carry a weak negative tension. At the sending station there are provided three relays 22, 23, and 24 with armatures 25, 26, and 27, the functions of which will be further explained here below. The negative pole of the battery 2 is connected to the working contact of the armature 25, the armature itself being connected to the conductor 1.

At the receiving station B there are provided, in addition to the receiving devices mentioned above, a local battery 28, a minus-polarized relay -29, two plus-polarized relays +30 and +31, and non-polarized relays 32, 33, 34, 35, and finally a relay 36 which may be either polarized or non-polarized, preferably polarized, however. All these relays are provided with armatures 37, 38, 39, 40, 41, 42, 43, and 44, respectively. The conductor 1 is connected to the armature 40. The winding of the relay 36 is connected with the secondary winding 45 of an induction coil, the primary winding 46 of which is connected between the armature 37 and the lamps I', II', and III'.

When operating the arrangement, the contact drum 3 rotates all the time in the direction indicated by the arrow. If it is desired to cause the lamp I' at the receiving station to light the key I is pressed down which only effects a single contact. When at the rotation of the drum 3 the brush 15 comes into contact with the bar 6, the following circuit will therefore become closed: from the positive pole of the battery 2 through the brush 15, the bar 6 and the ring 4, the brush 16, the relay 24, and the pressed-down key I to the middle point of the battery. The relay 24 is thus excited and attracts its armature 27 against its working contact, which causes the following new circuit to become closed: from the positive pole of the battery 2 through the armature 27, the relay 24, and the key I to the middle point of the battery. The relay 24 thus locks itself as long as the key I is pressed down. At the same time the bars

7, 9, 11, etc., in the contact drum 3 connected to each other, obtain a positive tension from the battery 2 over the armature 27, the brush 16, and the ring 4 and cross section between the latter and bar 7. When after about one rotation of the drum 3 the brush 14 now makes contact with the bar 6, the following circuit becomes closed: from the positive pole of the battery 2, through the armature 27, the brush 16, the ring 4 and the bar 6, the brush 14, the relay 23, the relay 22, and the key I to the middle point of the battery. Both relays 23 and 22 thus become excited and attract their respective armatures 26 and 25. The relay 23 hereby locks itself, so that the current passes from the armature 27 through the armature 26, the working contact of this armature, and the relay 23, to the relay 22 and through the key I to the middle point of the battery. On account of the attraction of the armature 25 a negative current may flow from the negative pole of the battery 2 through the working contact 47 of the armature 25, and through the armature 25 to the line 1.

At the receiving station this negative current reaches the armature 40 (of the relay 32) and passes from this armature to the plus-polarized relay +30, which does not become attracted by this negative current, and through the conductor 48 to the minus-polarized relay -29 and to the earth. The armature 37 of this relay thus becomes attracted, on account of which a circuit becomes closed from the positive pole of the battery 28, through the armature 42, the lamp I', the primary winding 46, and the armature 37, to the battery 28. The lamp I' is thus made to light.

When the key I at the sending station A is released, the circuits through the relays 24, 23, and 22 become broken, and the armatures of these relays become released. On account hereof the negative current becomes broken at 47. On account of the breaking of the negative current the armature 37 of the relay -29 at the receiving station is released, hence the local circuit to the lamp I' becomes broken and the lamp goes out.

When a negative current is sent out from the sending station A to the line 1 the lamp I' at the receiving station B is thus lighted and it will remain burning as long as the current lasts.

If, on the other hand, a signal of the lamp II' is desired, the key II at the sending station A is pressed down. This key comprises two pairs of contacts 49 and 50, the pair 49 of which corresponds to the key I. By pressing down the key II, that is to say by closing these two pairs of contact, it is first attained at the rotation of the contact drum 3, in the same manner as described above, that the relay 24 be-

comes excited and locks itself so that the ring 4 and the bars 7, 9, etc., obtain a positive tension. When at the continued rotation of the drum 3 the brush 18 now 5 comes into contact with the bar 7, a positive pulsation may thus flow from the positive pole of the battery 2, through the armature 27, the brush 16, the ring 4, the bar 7, the brush 18, the pair of contacts 10 50, the conductor 51, and the armature 25, to the line 1. When at continued rotation of the contact drum 3, the brush 14 comes into contact with the bar 6, the relays 22 and 23 become excited in the same manner 15 as described above, on account whereof the armature 25 will be switched into contact with the working contact 47. A negative pulsation then flows from the negative pole 20 of the battery 2, through the contact 47, and the armature 25, to the line 1. By pressing down the key II a positive pulsation will thus be sent out to the line 1 and afterward a negative pulsation.

The positive pulsation reaches the armature 40 at the receiving station B and flows from this armature to the plus-polarized relay +30, which is thus excited, and through the conductor 48 to the minus-polarized relay -29, which is not actuated by this positive pulsation, and to the ground. Owing to the excitation of the plus-polarized relay +30 its armature 38 becomes attracted, so that a circuit is closed from the positive pole of the battery 28, through the armature 38, the relay 34, the armature 44, and to the battery 28. Hereby the armature 42 of the relay 34 becomes attracted, so that a new circuit becomes closed from the battery 28, through the armature 42, the 40 relay 34, the armature 44, back to the battery 28. The relay 34 hereby locks itself. When the positive pulsation ceases, and the armature 38 of the relay +30 is released, a new circuit is therefore formed from the 45 battery 28 through the armature 42, the contact 52, the armature 38, the relay 32, the armature 44, to the battery 28, whereby the relay 32 becomes excited and its armature 40 becomes attracted. The incoming negative pulsation will then pass through the armature 40, the contact 54, the armature 41, the plus-polarized relay +31 which does not become actuated by the same, the conductor 48, and the minus-polarized relay 50 -29 to the ground. Hereby the armature 37 becomes attracted so that a new circuit is formed from the battery 28, the armature 42, the contact 53, the armature 43, the lamp II', the primary winding 46, and the armature 37, to the battery 28. The lamp II' is thus made to burn.

When the key II at the sending station A is released, the circuits through the contacts 49 are broken in the same manner as 60 for the key I, so that the relays 22, 23, and

24, become demagnetized, on account of which the negative current becomes broken at 47 owing to the release of the armature 25. When the negative pulsation ceases on account hereof the armature 37 at the receiving station B is released, hence the local current through the lamp II' becomes broken and the lamp goes out.

When the circuit through the lamp II' and through the primary winding 46 becomes 75 broken a current is generated at the moment of breaking in the secondary winding 45, which current passes through the relay 36. As stated above, this relay is preferably polarized, and in such case it is polarized 80 in such manner that it becomes actuated by the current generated in the secondary winding 45 when the current in the primary winding 46 becomes broken, not however by the current generated in the secondary winding 45, when the current is closed in the primary winding 46. It is of course not necessary, however, that the relay 36 be polarized, as the current induced in the secondary winding 45 becomes less when the 90 current in the primary winding 46 is closed, than when it is broken, and the relay 36 might therefore be adjusted in such manner that it would only be caused to operate by the stronger current generated when the 95 current in the primary winding 46 is broken. When at the breaking of the current through the primary winding 46 a current of short duration flows through the relay 36, this relay becomes excited and attracts its armature 44. The circuits through the relays 32 and 34 thus become broken so that their armatures 40 and 42 return to their normal positions. All apparatus at the receiving station B are then in the positions which they assumed before the positive pulsation reached the station.

By pressing down the key II at the sending station A a short positive pulsation and a long negative pulsation are thus sent out 110 through the line 1, which pulsations cause the lamp II' at the receiving station B to burn as long as the key II is pressed down. When pressing down a key the positive pulsations, if any, always become short, while the negative pulsation or current lasts as long as the key is pressed down, this being the pulsation operating the signal selected by the positive pulsations.

If the key III at the sending station A is pressed down, it is first attained, when the bar 6 passes the brush 15, that the relay 24 becomes excited, and locks itself, in the manner above described with reference to the keys I and II, so that the ring 4 and the bars 7, 9, 11, 13 obtain a positive tension. When on the continued rotation of the drum 3 the brush 19 is passed by the bars 7 and 9, two positive pulsations may flow from the positive pole of the battery 2, 125 130

through the armature 27, the brush 16, the ring 4, and cross connection between the latter and bar 7, through one of the bars 7 and 9, to the brush 19, the right-hand pair 5 of contacts of the key III, the conductor 51, and the armature 25, to the line 1, in similar manner as above described with reference to the key II. After every positive pulsation a negative pulsation is sent out 10 through the brush 19 when it is passed by the bars 8 and 10, which, as previously described, are connected to the ring 5 which obtains a weak negative tension from the battery 2. The purpose of these negative 15 pulsations is to discharge the line after every positive pulsation. These negative pulsations are not to be so strong, however, that they might actuate the minus-polarized relay —29, and from this upper limit their 20 strength may be varied downward to zero, that is to say that the line is merely grounded after each positive pulsation. Immediately after these two positive pulsations have been sent out, and when on the 25 continued rotation of the drum 3, the brush 14 is passed by the bar 6, the relays 22 and 23 will become excited in the same manner, and the same circuits will be formed, as above explained with reference to the keys 30 I and III, with the exception only that the left-hand contacts of the key III are included in the circuits, instead of the contacts of the key I or the contacts 49 of the key II. As above described, the armature 35 25 of the relay 22 will be switched into contact with the working contact 47, and a negative current will flow from the negative pole of the battery 2, through the contact 47, and the armature 25, to the line 1, 40 which current will last as long as the key III is pressed down.

44 III is pressed down. The first one of the positive pulsations effects at the receiver station B the switching of the relays +30, 34, and 32, as described above. The second positive pulsation then flows through the armature 40, the contact 54, to the armature 41, and through the plus-polarized relay +31, which will then attract its armature 39.

45 50 Hereby the armature 43 of the relay 35 becomes attracted in the same manner as described above for the lamp II', and when the pulsation ceases the armature 41 of the relay 33 becomes attracted. The incoming negative pulsation then flows through the armature 40, the contact 54, the armature 41, the contact 55, the conductor 56, the conductor 48, and the minus-polarized relay -29, to the ground. Hence a circuit will be closed from the battery 28, through the armature 42, the contact 53, the armature 43, the contact 57, the armature 58, the lamp III', the primary winding 46, and the armature 37, to the battery, thus making the lamp light. When the key III at the

46 60 65

sending station A is released, the lamp III' goes out in the same manner as described with respect of the lamp II'.

The sending station A as well as the receiving station B may of course be arranged for a practically unlimited number of keys, or signal receiving devices. This is indicated in the drawing at the sending station A by means of the brushes 20 and 21, and at the receiving station B by means of the armature 58 corresponding for the next lamp to the armature 43 for the lamp III'. The conductor 56 corresponds for the next lamp to the circuit through the armature 41 and the plus-polarized relay +31 for the lamp III'. 70 75 80

Figs. 2 to 5 show a few modifications of the arrangement of the receiving station B in Fig. 1, each of these figures showing an alteration of the connection below the lines E, F, G, and H in Fig. 1. Fig. 2 shows a parallel connection instead of a series connection of the plus-polarized and minus-polarized relays. An incoming positive pulsation from the line 1 flows in this case partly through E to the relay -29 without actuating it, and through F to the ground, and partly through H to the relay +30, which becomes excited, and through the armature 40 and through G to the ground. If still another positive pulsation comes in before the negative pulsation this positive pulsation also flows partly through E, the relay -29, and F to the ground and partly through H, the relay +31, the armature 41, the contact 54, and the armature 40 through G to the ground. The negative pulsation in this case flows through H and the plus-polarized relays, which do not become actuated, and through G to the ground, and besides through E to the minus-polarized relay -29 and through F to the ground.

Fig. 3 shows an arrangement according to which only one plus-polarized relay is used at the receiving station B. In this case the plus-polarized relays +30 and +31 in Fig. 1 are substituted by ordinary non-polarized relays. The line 1 is connected to a plus-polarized relay +59. This relay will thus not become actuated by a negative pulsation, but such pulsation flows through the relay and through F to the relay -29 and back through E to the ground, the armature 37, of course, becoming attracted. If the negative pulsation is preceded by a positive pulsation, on the other hand, the armature 60 of the relay +59 becomes attracted, the relay -29 remaining unactuated. Owing to the attraction of the armature 60 a local circuit is closed from the battery 61, through the armature 40, the relay 30 (which is now non-polarized) through H and the armature 60 to the battery. Owing to the excitation of the relay 30 the circuits through the relays 32 and 34 become closed 130

in the same manner as described above. If a second positive pulsation comes in immediately afterward this pulsation will again attract the armature 60, on account where-
 5 of a current is again sent out from the bat-
 tery 61, which current in such case flows
 through the armature 40, the contact 54, the
 armature 41, the (non-polarized) relay 31,
 and through H and the armature 60 to the
 10 battery. At the subsequent negative pulsation
 the lamp III' will be made to glow.

Fig. 4 shows the alteration to Fig. 3 that the local battery 64 is connected in series with a resistance 65 between G and H and in
 15 parallel with the armature 63 of the plus-polarized relay +62. The armature 63 nor-
 mally short-circuits the (non-polarized) re-
 lay 30 so that practically no current from
 the battery 64 flows through the same. When
 20 the armature 63 becomes attracted by a posi-
 tive pulsation through the relay +62, how-
 ever, the short circuit through 63 becomes
 broken and the current from the battery 64
 25 excites the relay 30 in the same manner as
 for Fig. 3. The advantage of this arrange-
 ment as compared with that shown in Fig. 3,
 is of course decreased sparking in the con-
 tact, as the circuit through the battery does
 30 not become broken, but only the short-cir-
 circuit.

Fig. 5 shows an arrangement according to which only one polarized relay is used at the receiving station, without any additional local battery. An incoming positive pulsation
 35 excites the plus-polarized relay +66 so that the armature 67 becomes attracted, whereby the positive pulsation will flow through H and, as described above, excite the relay 30, which is not now plus-polarized. A second
 40 immediately following positive pulsation will excite the relay 31. The negative pulsation will not influence the relay +66, how-
 ever, but flows through the armature 67 of the same and through F to the minus-polar-
 45 ized relay -29.

Fig. 6 illustrates an arrangement in which two line wires, for instance two telephone wires, and the earth, or instead of the earth a third wire, are used for transmitting the
 50 pulsations from the sending station A¹ to the receiving station B¹. This arrangement is particularly intended for transmitting type-writing. In order to simplify the drawing, however, only nine keys have been
 55 shown at the sending station, and at the receiving station only nine electromagnets for operating nine keys of the typewriter. In order to make Fig. 6 more perspicuous the references in the same correspond to the
 60 references used in Fig. 1, so that for instance the part in Fig. 6 corresponding to the part 4 in Fig. 1 has been referenced 104, the part corresponding to the part 16 is referenced 116, the key II corresponds to the key II^a,
 65 and so forth.

At the sending station A¹ there is pro-
 vided, as at the station A in Fig. 1, a battery
 102, a contact drum 103 with rings and bars
 104 to 109, and brushes 114 to 119, relays
 122, 123, 124, with armatures 125, 126, 127,
 70 and keys I^a, II^a, III^a which are arranged as
 the keys I, II, III in Fig. 1, and through the
 latter two of which positive pulsations may
 be sent out through the conductor 151 to the
 line 101. There are further keys IV^a to IX^a,
 75 which are arranged in groups of three, IV^a
 to VI^a, and VII^a to IX^a, in the same manner
 as I^a to III^a, with the difference that they
 are provided with an additional pair of con-
 tacts connected through a conductor 251,
 80 and through the armature 225 of a relay 222
 in series with the relay 122, to the line 201.
 On the other hand these contacts are con-
 nected with the brushes 118, 119 so that posi-
 tive pulsations may be sent out through the
 85 same to the line 201. On the other hand the
 relay 222 is not provided with any working
 contact corresponding to the contact 147 of
 the relay 122, on account whereof no nega-
 tive pulsation can flow to the line 201 apart
 90 from those weak negative pulsations which
 follow every positive pulsation and which
 serve only for discharging the line but which
 cannot actuate any apparatus at the receiv-
 ing station.

In the same manner as for Fig. 1, when
 the key I^a is pressed down a negative puls-
 ation flows out into the line 101, when the key
 II^a is pressed down one positive and one
 negative pulsation, and for the key III^a two
 100 positive and one negative pulsation in the
 line 101. When pressing down the keys
 IV^a, V^a, and VI^a the same pulsations are re-
 spectively obtained in the line 101, but for
 each key a positive pulsation is sim-
 105 taneously obtained in the line 201, as will be
 easily understood from the drawing. When
 pressing down the keys VII^a, VIII^a, and
 IX^a the same pulsations are also obtained
 in the line 101 as for the keys I^a, II^a, and
 110 III^a respectively, but at the same time two
 pulsations are obtained in the line 201 for
 each key. Thus for each key a different
 combination of pulsations in the line con-
 ductors 101 and 201 is obtained.

For the line 101 there are provided at the
 receiving station B¹ apparatus correspond-
 ing to those at the station B in Fig. 1, viz.
 a battery 128, a minus-polarized relay -129,
 two plus-polarized relays +130 and +131,
 120 non-polarized relays 132, 133, 134, and 135,
 and a relay 136, preferably but not neces-
 sarily polarized, all these relays being pro-
 vided with armatures 137 to 144. Each of
 the relays 134 and 135 is here provided with
 125 a pivoted contact 342 and 343, respectively.
 There will also be found in the drawing a
 pivoted contact 358 being a corresponding
 contact in the next group of relays. These
 three contacts are normally in contact with
 130

conductors 175, 176, and 177, respectively, to each of which one pole of three of the magnets I^a to IX^a is connected, as shown in the drawing. In the circuit of the relay 5 136 the secondary winding 145 is connected, the primary winding 146 of which is connected between the battery 128 and the armature 137.

Only positive active pulsations flow

10 through the line 201, for which reason there is provided no relay for this line corresponding to the minus-polarized relay —129, and no plus-polarized relays are required, but all relays 230, 231, 232, 233, 234, 15 and 235 are non-polarized. In other respects the arrangement of the relays and circuits provided for the line 201 corresponds to the arrangement at the station B in Fig. 1 and is similar to the arrangement of the relays 20 and circuits provided for the line 101. The relays are provided with armatures 236 to 243, the two latter relays being provided with a pivoted contact 442 and 443, respectively. These contacts and the corresponding pivoted contact 458 of the next group of 25 relays are normally in contact with conductors 275, 276, and 277, respectively, corresponding to the conductors 175, 176, and 177, as shown in the drawing.

30 If a single negative pulsation comes in from the line 101 the different groups of relays remain unactuated, but the relay —129 becomes excited so that the local current from the battery 128 will flow to the conductor 175. If the negative pulsation is

35 preceded by a positive pulsation the armature 142 and contact 342 of the relay 134 will be switched against the contacts 152 and 153 and the negative pulsation will pass

40 through the armature 140, contact 154, armature 141, relay +131, and relay —129, in similar manner as described with reference to Fig. 1 and the operation of relay 34 by relay +30 by a positive pulsation and

45 relay —29 by a negative pulsation, when the current from the battery 128 will flow through the contact 342, the contact 153, and the armature 343, to the conductor 176. If the negative pulsation is preceded by two

50 positive pulsations in the line 101 the current from the battery 128 will flow to the conductor 177 through the armature 137, contact 342, contact 153, contact 343, and contact 358, the operation of the relays

55 +130, 134, 132, +131, 135, 133, and —129, and the circuits formed being similar to those described with reference to Fig. 1 and the sending of the current from the local battery 28 through the lamp III'. The

60 pulsations sent out through the line 101 will thus determine the conductor 175, or 176, or 177 to which the positive pole of the battery 128 will be connected. When one of the keys I^a, IV^a, and VII^a at the sending station is pressed down the local current at

the receiving station will thus flow to the conductor 175, for either of the keys II^a, V^a, or VIII^a it will flow to 176, and for either of III^a, VI^a or IX^a to 177. Which one of the magnets I^a to IX^a will become excited 70 evidently depends upon through which of the conductors 275, 276, and 277 the local current can return to the battery 128. If no pulsation has been sent out on the line 201, but the apparatus connected to this line 75 occupy the positions shown, the current may evidently return through the conductor 275 and the contact 442 to the battery.

The arrangement of the relays and circuits provided for the line 201 being similar 80 to those provided for the line 101 and to the relays and circuits at the station B in Fig.

1, it will be understood that if one pulsation is sent out from the sending station A¹ through the line 201 it will energize the 85

relay 230, which attracts its armature 238, which closes the circuit of the relay 234, which attracts its armature 242 and locks itself. The pivoted contact 442 is thus

switched over against the contact 253, so 90 that connection is established between the negative pole of the battery 128 and the conductor 276 through contact 442, contact 253, and contact 443. Simultaneously, the

connection between the conductor 275 and the negative pole of the battery is broken at the contact 442. If only one pulsation is

sent out on the line 201 the conductor 276 will thus be connected with the battery. When the pulsation ceases the armature 238 100

is released and closes the circuit of the relay 232, which attracts its armature 240. If a second pulsation is sent out on the line 201 such second pulsation will thus pass through

armature 240 to armature 241 and through 105 relay 231, which attracts its armature 239, which closes the circuit of the relay 235, which attracts its armature 243 and locks itself, breaking the connection between the

pivoted contact 443 and the conductor 276 110 and establishing connection between the conductor 277 and the negative pole of the battery 128 through contact 458, contact 443, contact 253, and contact 442.

When depending on the pulsations sent 115 out, the local current may only flow into one of the conductors 175, 176, and 177, and only return through one of the conductors 275, 276, and 277, it will be understood that

for every key pressed down at the sending 120 station only one certain magnet at the receiving station becomes actuated.

By enlarging the sending station A¹ by providing the roller 103 with four additional brushes and four additional positive 125 bars, and by providing seven rows of seven contacts, it is possible by means of only

seven combinations of pulsations on each line to operate $7 \times 7 = 49$ different types or other apparatus at the receiving station. 130

For this purpose the receiving station must of course be provided with a corresponding number of groups of relays, that is to say six groups of each line.

5 It will be understood that the plus-polarized relays +130 and +131, and so forth, may be substituted by non-polarized relays by providing a single relay as shown in Figs. 3, 4 or 5.

10 The armatures of the polarized relays may either be permanent magnets or be magnetized by a separate source of current. All relays may be membrane relays or spring relays or other rapidly operating relays.

15 I claim:

1. In a selective control system, the combination of means at the sending station for sending to the receiving station positive as well as negative pulsations in variable se-

20 quence and number, an electrical connection between the sending station and the receiving station, receiving apparatus at the receiving station, circuits controlling the said receiving apparatus, relays at the receiving

25 station at least one of said relays being polarized and adapted to be actuated by pulsations of one polarity, said relays controlling the said circuits for selective connection of different receiving apparatus according to

30 the number of pulsations of the polarity of said polarized relay, a source of current at the receiving station, and at least one polarized relay at the said station adapted to be actuated by pulsations of the other

35 polarity and controlling the said source of current so as to connect the same to the receiving apparatus selected by the first-named relay, substantially as and for the purpose set forth.

40 2. In a selective control system, the combination of means at the sending station for sending to the receiving station positive as well as negative pulsations in variable sequence and number, an electrical connection

45 between the sending station and the receiving station, receiving apparatus at the receiving station, at least one relay at the receiving station adapted to be actuated by pulsations of one polarity, a circuit arranged

50 to be closed by the said relay when it receives a pulsation of this polarity, a second relay in said circuit adapted to break a connection to one receiving apparatus when the said circuit is closed and to establish con-

55 nection to a second receiving apparatus, a second circuit controlled by the said relays and arranged to be closed when the pulsation in the first relay ceases, a third relay in said second circuit arranged when the cir-

60 cuit is closed to open a connection to a third receiving apparatus, a source of current at the receiving station, and at least one relay at the said station adapted to be actuated by pulsations of the other polarity and con-

65 trolling the said source of current so as to

connect the same to the receiving apparatus selected by the first named relay, substantially as and for the purpose set forth.

3. In a selective control system, the combination of means at the sending station for sending to the receiving station positive as well as negative pulsations in variable sequence and number, an electrical connection between the sending station and the receiving station, receiving apparatus at the receiving station, at least one relay at the receiving station adapted to be actuated by pulsations of one polarity, a circuit arranged to be closed by the said relay when it receives a pulsation of this polarity, a sec-

80 ond relay in said circuit adapted to break a connection to one receiving apparatus when the said circuit is closed and to establish connection to a second receiving apparatus, a second circuit controlled by the said re-

85 lays and arranged to be closed when the pulsation in the first relay ceases, a third relay in said second circuit arranged when the circuit is closed to open a connection to a

90 third receiving apparatus, a source of current at the receiving station, at least one relay at the said station adapted to be actuated by pulsations of the other polarity and controlling the said source of current so as to

95 connect the same to the receiving apparatus selected by the first named relay, an induction coil the primary winding of which is connected in the circuit of the said source of current, a relay connected in the circuit of the secondary winding of said induction

100 coil, said relay controlling the said first and second circuits established through the excitation of the relay of the first polarity and adapted to break the same when at the ceas-

105 ing of the pulsation through the relay of the other polarity and at the consequent breaking of the circuit through the receiving apparatus a current is induced in the secondary winding at the moment of breaking, substantially as and for the purpose set forth.

4. In a selective control system, the combination of means at the sending station for sending to the receiving station positive as well as negative pulsations in variable sequence and number, said means comprising a rotary contact drum, contact rings on said drum,

115 contact bars on said drum, brushes bearing against the said drum, keys provided with contacts connected with the said brushes, a circuit comprising two of the brushes and connected to contacts at the keys in such

120 manner as to become closed when any of the keys is pressed down, a relay in said circuit, a source of current, a connection from one pole of the said source of current to the contact bars and controlled by the said relay in

125 such manner that when closed by the same 130

pulsations of a certain polarity may flow through these bars and through the brush connected with the key pressed down to the connection between the stations, at least one 5 relay at the receiving station adapted to be actuated by positive pulsations, at least one relay at the receiving station adapted to be actuated by negative pulsations, receiving apparatus at the receiving station, and circuits 10 controlling the said receiving apparatus and adapted to be closed and broken by means of the said relays according to the sequence and the number of the positive and negative pulsations, substantially as and for 15 the purpose set forth.

5. In a selective control system, the combination of an electric connection between the sending station and the receiving station, means at the sending station for sending 20 to the receiving station positive as well as negative pulsations in variable sequence and number, said means comprising a rotary contact drum, contact rings on said drum, contact bars on said drum, brushes bearing 25 against the said drum, keys provided with contacts connected with the said brushes, a circuit comprising two of the brushes and connected to contacts at the keys in such manner as to become closed when any of the 30 keys is pressed down, a relay in said circuit, a source of current, a connection from one pole of the said source of current to the contact bars and controlled by the said relay in such manner that when closed by the 35 same pulsations of a certain polarity may flow through these bars and through the brush connected with the key pressed down to the connection between the stations, a second circuit adapted to be closed by the said 40 relay after a certain interval of time, a second relay in said second circuit adapted to break the connection for the said pulsations from the said contact bars to the connection between the stations and to connect the opposite pole of the said source of current to the said connection between the stations, at least one relay at the receiving station adapted to be actuated by positive pulsations, at least one relay at the receiving 45 station adapted to be actuated by negative pulsations, receiving apparatus at the receiving station, and circuits controlling the said receiving apparatus and adapted to be closed and broken by means of the said relays according to the sequence and the number 50 of the positive and negative pulsations, substantially as and for the purpose set forth.

6. In a selective control system, the combination of an electric connection between 60 the sending station and the receiving station, means at the sending station for sending to the receiving station positive as well as negative pulsations in variable sequence and number, said means comprising a rotary contact drum, contact rings on said drum, 65

contact bars on said drum, brushes bearing against the said drum, keys provided with contacts connected with the said brushes, a circuit comprising two of the brushes and connected to contacts at the keys in such 70 manner as to become closed when any of the keys is pressed down, a relay in said circuit, a source of current, a connection from one pole of the said source of current to the contact bars and controlled by the said relay 75 in such manner that when closed by the same pulsations of a certain polarity may flow through these bars and through the brush connected with the key pressed down to the connection between the stations, bars on said 80 roller between the said contact bars and connected with a weak polarity opposing the polarity supplied to the said contact bars, a second circuit adapted to be closed by the said relay after a certain interval of time, a second 85 relay in said second circuit adapted to break the connection for the said pulsations from the said contact bars to the connection between the stations and to connect the opposite pole of the said source of current to the said connection between the stations, at least one relay at the receiving station adapted to be actuated by positive pulsations, at least one relay at the receiving 90 station adapted to be actuated by negative pulsations, receiving apparatus at the receiving station, and circuits controlling the said receiving apparatus and adapted to be closed and broken by means of the said relays according to the sequence and the number 95 of the positive and negative pulsations, substantially as and for the purpose set forth.

7. In a selective control system, the combination of two electric connections between the sending station and the receiving station, means at the sending station for sending to the receiving station positive as well as negative pulsations in variable sequence and number, said means comprising a rotary contact drum, contact rings on said drum, contact bars on said drum, brushes bearing against the said drum, keys provided with contacts connected with the said brushes, a circuit comprising two of the brushes and connected to contacts at the keys in such manner as to become closed when any of the keys is pressed down, a relay in said circuit, a source of current, a connection from one pole of the said source of current to the contact bars and controlled by the said relay in such manner that when closed by the same pulsations of a certain polarity may flow through these bars and through the brush connected with the key pressed down to both connections between the stations, a second circuit adapted to be closed by the said relay after a certain interval of time, a second relay in said second circuit adapted to break the connection for the said 125

105

115

120

125

130

pulsations from the said contact bars to one of the connections between the stations and to connect the opposite pole of the said source of current to the said connection between the stations, a third relay in the said second circuit adapted to break the connection for the said pulsations from the said contact bars to the other connection between the stations, receiving conductors at the receiving station, receiving apparatus connected between the said receiving conductors, at least one relay at the receiving station connected to the first named connection between the stations and adapted to be actuated by pulsations of one polarity in the same and controlling half the number of the said receiving conductors for selective connection of the same according to the

number of pulsations of this polarity, means at the receiving station connected to the other connection between the stations and controlling the other half number of the said receiving conductors for selective connection of the same according to the number of pulsations in said second connection, a source of current at the receiving station, and at least one relay at the receiving station adapted to be actuated by pulsations of the other polarity in the first-named connection between the stations and controlling the said source of current so as to connect the same to the receiving conductors selected by the first-named relay and by the said means, substantially as and for the purpose set forth.
